G. W. NEWBERRY

PAPERHANGER'S SHEARS HOLDER

Filed Jan. 17. 1923

INVENTOR
George W. Newberry
BY
John C. Higdon
ATTORNEY

UNITED STATES PATENT OFFICE.

GEORGE W. NEWBERRY, OF ST. LOUIS, MISSOURI.

PAPERHANGER'S SHEARS HOLDER.

Application filed January 17, 1923. Serial No. 618,145.

To all whom it may concern:

Be it known that I, GEORGE W. NEWBERRY, a citizen of the United States, residing at St. Louis, in the State of Missouri, have invented certain new and useful Improvements in Paperhangers' Shears Holders, of which the following is a specification containing a full, clear, and exact description, reference being had to the accompanying drawing, forming a part hereof.

My invention consists in the novel construction and combination of parts herein-after particularly described and distinctly claimed.

The object of my invention is to provide an improved flexible shears holder that is adapted to be pinned to the overall-leg of the user of my invention, and which holder may be quickly detached therefrom when the overalls are to be sent to the laundry, and which may be quickly attached to the overall-leg when again required for use; and which holder will be simple in construction, durable, and of low cost to manufacture.

In the drawing:—

The figure represents a portion of the leg of a pair of overalls, showing the manner in which my invention is applied thereto when in use.

In carrying out my invention, I make use of a common safety-pin 1, which has its pointed portion inserted through the overall-leg 2 of the user of my invention.

The numeral 3 designates a flexible base that is preferably in the form of a rectangular piece of leather, having provided at its upper end a flap 4, that is made integral therewith, and is adapted to be bent or looped around the main body portion of the said safety-pin 1.

The said flap 4 is then riveted to the said piece of leather 3 by means of rivets 5.

The numeral 6 designates a narrow strip of leather having its opposite ends secured to the said piece of leather 3, by means of rivets 7.

In manufacturing my invention, the said strip of leather 6 when cut, should be of greater length than that of the width of the leather 3, so that when the said strip 6 is

riveted to the leather 3, a loop 8 will be formed about the center of the said strip 6, through which loop a pair of paperhangers' shears 9 or other tool is slipped.

The shears 9 are conveniently supported with one of their handle-breasts resting upon the upper edge of said loop 8; but with the upper portions of both handles free, and ready to be grasped by the workman, to quickly withdraw the shears from said loop, when the shears are to be used.

No other support for the shears is necessary, and the blades thereof extend free below said loop 8, and a considerable distance below the lower edge of the flexible base 3.

The holder-base 3, being soft and flexible will readily bend during use, without danger of cracking or breaking.

While I have illustrated certain details which I deemed to be particularly effective, and have illustrated a construction which is very cheap to make and easily assembled, I do not wish to be limited to these details, as it is obvious that many changes might be made therein without departing from the spirit or scope of my invention, as for instance;—my invention may be made of material other than leather, and may be made in different sizes to hold different tools, such as a screw-driver, a pair of pliers, a painter's dust-brush, a paint-brush, a hammer, a transfer punch for conductors, and many other articles too numerous to mention.

What I claim as new and desire to secure by Letters Patent is:—

A flexible shears-holder, comprising a leather base having at its upper end an integral flap adapted to be bent or looped around the main body portion of a safety-pin, and a strip of leather secured across the outer face of said leather base to provide a shears-holding loop at about the center of the length of said strip.

In testimony whereof, I have signed my name to this specification in presence of two subscribing witnesses.

GEORGE W. NEWBERRY.

Witnesses:

EDNA E. CONRAD,
HENRY L. HIGDON.
